CLAIM

The ornamental design for a set of sorting trays for puzzles with lid as shown and described.

DESCRIPTION

1 Set of sorting trays for puzzles with lid

1.1: Top, left, front perspective view of two sorting trays for puzzles with a single lid;

1.2: Top, front perspective view of a single sorting tray for puzzles shown in Rep. 1.1, the second sorting tray being identical thereto, and lid therefor;

1.3: Top, back perspective view of a single sorting tray for puzzles shown in Rep. 1.1, the second sorting tray being identical thereto, and lid therefor;

1.4: Top, left front perspective view of a single sorting tray for puzzles shown in Rep. 1.1, the second sorting tray being identical thereto, and lid therefor;

1.5: Top, right front perspective view of a single sorting tray for puzzles shown in Rep. 1.1, the second sorting tray being identical thereto, and lid therefor;

1.6: Top plan view of a single sorting tray for puzzles shown in Rep. 1.1, the second sorting tray being identical thereto, and lid therefor.

(Continued)

The dash-dash broken lines showing additional sorting trays in Rep. 1.1 depict environmental subject matter that form no part of the claimed design.

1 Claim, 6 Drawing Sheets
